UNITED STATES PATENT OFFICE.

ALEXANDER SLAYSMAN, JR., OF HAMILTON, MARYLAND.

DRIER.

1,139,815.

Specification of Letters Patent. Patented May 18, 1915.

Application filed December 15, 1914. Serial No. 877,398.

To all whom it may concern:

Be it known that I, ALEXANDER SLAYSMAN, Jr., a citizen of the United States, residing at Hamilton, Baltimore county, and 5 State of Maryland, have invented certain new and useful Improvements in Driers, of which the following is a specification.

This invention relates to driers.

One object of the invention is to provide 10 a simple, economical and sanitary apparatus particularly designed for the purpose of drying can ends whether it be desired to remove moisture from the can ends to prevent rust or whether it be desired to dry an adhesive or sealing compound which has been 15 applied thereto.

Another object resides in the provision of 20 means for effectually drying can ends or other articles embodying among other characteristics means whereby the can ends may be fed to a heating chamber heated through the instrumentality of any suitable heating medium and caused to travel over a zig-zag course through the chamber in the presence 25 of the heating medium and finally discharged automatically out of the heating chamber.

A still further object resides in the provision of a machine of the nature stated embodying among other characteristics, means 30 whereby the can ends or other articles are transferred from one set of rotatable elements to another set of rotatable elements and back onto the first set of rotatable elements and so on, whereby the can ends take 35 a zig-zag course through the heating chamber until they reach a point in their zig-zag course when they are tripped and caused to be ejected automatically out of the heating 40 chamber.

With the above and other objects in view, the present invention consists in the combination and arrangement of parts herein-after more fully described, illustrated in the 45 accompanying drawings, and particularly pointed out in the appended claims, it being understood that changes may be made in the form, proportion, size and minor details without departing from the spirit or sacrificing any of the advantages of the invention.

In the drawings: Figure 1 is a perspective view of the invention. Fig. 2 is a transverse sectional view. Fig. 3 is a longitudinal sectional view, and Fig. 4 is a plan view with 55 the closure of the heating chamber open.

Referring now more particularly to the accompanying drawings, the reference character 10 indicates a table of any suitable character for the support of the mechanism 60 embodied in the present invention, and this table may be supported in any suitable manner, one means being to provide oppositely disposed legs 11 and 12 of any suitable character at opposite ends of the table. 65

The legs 11 may be connected by a bracing element 13, if desired, and the opposite legs at each end of the table may be connected by a brace 14, if desired. The table and its legs and brace connections are composed of 70 angle iron in part or in whole or any suitable character of material may be employed. Secured to the underside of the table 10 are a pair of hangers 15 and 16 provided with bearings 17 in which may be journaled a 75 drive shaft 18 provided on its outer end with a pulley 19 or any other suitable means by which the drive shaft 18 may be driven. A driven shaft 20 is journaled in suitable 80 bearings 21 mounted preferably on the connecting pieces 14 between the end legs 11 and 12 and also preferably journaled in the hangers 22 disposed in alinement with the bearings 21. The driven shaft 20 is driven through the instrumentality of the driving 85 shaft 18 in any suitable manner, one means being to provide the driving shaft 18 with a beveled gear 23 adapted to mesh with a beveled gear 24 on the driven shaft 20. Mounted on the upper face of the table 10 90 is disposed a suitable heating means for drying purposes, as will be explained. This heating means may consist of a coil 25 to receive steam, water, air or other drying medium. The table 10 is provided with 95 apertures 26 and 27 beneath which the heads 28 and 29 of the bearings 30 and 31, respectively, may be disposed. In these bearings vertical shafts 32 and 33, respectively, are journaled, and which shafts extend through 100 the aforesaid apertures 26 and 27, respectively, in vertical parallel planes above the

65

table 10. The shaft 32 carries a beveled gear 34 adapted to mesh with a beveled pinion 35 keyed on the driven shaft 20. The shaft 33 carries a beveled gear 36 adapted to mesh 5 with a beveled pinion 37 keyed on the driven shaft 20.

Rotatably mounted on the heads 28 and 29 of the respective bearings 30 and 31 are bearings 38 and 39 of sleeves 40 and 41, respectively, which are keyed to the aforesaid shafts 32 and 33, respectively, in any suitable manner and which are therefore adapted for rotation with said shafts 32 and 33. The bearings 38 and 39 of the respective sleeves 40 and 41 are formed preferably by enlarging the lower ends of said sleeves forming shoulders 42 and 43, respectively.

Fixedly secured to the sleeves 40 and 41 are sets of like disks A and B. The disks 44 and 45 of the respective sets may be of any suitable form and may be secured to the respective sleeves 40 and 41 in any suitable manner as by shrinking, sweating or by means of suitable keys. In any event, the disks of each set are preferably arranged in vertical alinement one upon another with the disks of one set overlapping the disks of the adjacent set at a portion of the turn of revolution of the disks. The lowermost 30 disk *a* of the set A is preferably provided with a hub 46 which extends above and below the operative surface of the disk *a* and which hub 46 preferably bears against the shoulder 42 on the sleeve 40. The remaining upper disks *b*, *c* and *d* are preferably formed just like the disk *a* with their hubs arranged, the hub 46 of the disk *b* on the hub 46 of the disk *a*, with the remaining hubs of the remaining disks disposed one on 40 another, a set collar 47 being disposed on the sleeve 40 adjacent the hub of the uppermost disk *d*. Each disk has an annular flange 48 on its upper face, as shown. The disks may be and are preferably inclosed by a suitable 45 casing 49 provided with an inlet opening 50 with which cooperates an inlet chute 64 and an outlet opening 51 with which cooperates an outlet chute 65. The casing has its lower edge bolted or otherwise secured 50 around the edges of the table and preferably has a closure which is in the form of hinged sections 52 and 53 hingedly mounted as at 54 or in any suitable manner.

Each section 52-53 of the closure may be 55 fastened in closed position in any suitable manner, one means being to provide each section with a projection 55 which is bifurcated at its outer end, as at 56, for the reception of a screw threaded bolt 57 pivotally 60 mounted at one end, as at 58, in a bracket 59. By virtue of the pivots 58 the screw threaded bolt 57 may be thrown into and out of the bifurcations 56 of the projections 55 and, when placed in said bifurcations, the

bolts may be secured against movement on 65 their pivots by means of a thumb nut or other suitable element 60.

By virtue of the casing 49 and its closure there is provided a heating chamber C to retain the heating medium to provide for an 70 efficient drying of the can ends as they are fed over the zig-zag course between said sets of disks from the upper portion to the lower portion of the heating chamber, as will be better understood from a further reading 75 of this specification.

Mounted on the table 10 within the chamber C is an upright 61 on which may be keyed for adjustment by means of suitable fastening elements 62 a plurality of vertically spaced trip arms 63, there being one trip arm for each disk of each set of disks, the trip arms 63 of the set A being reversed with relation to position from the trip arms of the set of disks B, as clearly shown in 80 Fig. 4.

In the operation of the present drier power is applied to the pulley or other driving means 19 which causes rotation of the driving shaft 18. By reason of the gear 90 connections 23-24 between the driving shaft 18 and the driven shaft 20 the latter is caused to rotate when the driving shaft 18 is operated. By virtue of the gear connection 34-35 between the vertical shaft 32 and the driven shaft 30 said vertical shaft 32 and consequently the sleeve 40 secured thereto are adapted to rotate toward the right as indicated by the arrows in Fig. 3. The gear connection 36-37 between the vertical shaft 33 and the driven shaft 20 causes the vertical shaft 33 and consequently the sleeve 41 to rotate toward the right. This rotation of the vertical shafts 32 and 33 with their respective sleeves 40 and 41 causes the sets of disks A and B secured to said sleeves to rotate in opposite directions, and as previously stated, during the rotation of these sets of disks they overlap each other at one point in their turn of rotation.

The machine having been set in operation, the can ends, in order to dry them, because of their being wet and in order to prevent rust, or after a sealing compound has been applied thereto and in order to dry this 115 sealing compound, they are fed by hand or otherwise down the chute 64 onto the uppermost disk *d* of the set of disks A. The annular flange 48 on the disk *d*, and also as regards the other disks, form stops to limit the movement of the can ends inwardly of the disk and to cause the can end fed onto the disk *d* to lie between the annular flange 48 and the periphery of the disk. The disk *d* turning toward the right carries the can 120 end on it around to the corresponding trip 125 63 which trips and deflects the can end onto the uppermost disk *d* of the set B. The can

end is now turned to the right on the uppermost disk *d* which rotates to the right until it is brought into engagement with the corresponding trip arm 63 which co-operates 5 with the disk *d* of the set B when the can end is thrown onto the opposite disk *c* rotating toward the left and on which the can end remains until it is brought into engagement with the corresponding trip arm 10 63 when it is transferred diagonally across to the opposite disk *c* of the set B. This feed of the can end continues in this zig-zag way until the can end reaches the lowermost disk *a* of the set B when the trip arm 63' 15 will deflect the same onto the discharge chute 65 over which it is carried out through the discharge opening 51 in the casing 49 to a receptacle or any other suitable place effectually dried for the purposes hereinbefore 20 recited.

What is claimed is:—

1. In a can end drier, a suitably supported table, a casing on the table whose bottom is formed by said table and providing a heating chamber having an inlet at one end and an outlet at its opposite end, sets of oppositely disposed disks arranged within the heating chamber, means for rotating the sets of disks in opposite directions, one set of 25 disks overlapping the other set of disks at one point in their turn of rotation, means for heating the chamber, and means for transferring the can ends from one set of disks to the other set of disks alternately to 30 cause the can ends to travel over a zig-zag course through said chamber from the inlet to the outlet opening of the chamber.

2. In a drier, a chamber, means to heat the chamber, sets of rotatable disks in the chamber, means for rotating the disks in opposite 40 directions, and means to transfer articles from one disk of one set to a disk of the other set.

3. In a drier, a chamber, means to heat the chamber, sets of rotatable disks in the chamber, the disks of one set having a portion of their peripheral edges overlapping similar portions of the disks of the other set, means to feed articles to the uppermost disk of one 45 set, and means to transfer the articles from the disks of one set to the disks of the other set alternately to transfer the articles over a zig-zag course from the uppermost disk of one set to the lowermost disk of the other 50 set.

4. In a drier, a chamber, means to heat the chamber, sets of rotatable disks in the chamber, means for rotating the disks in opposite directions, and means to transfer articles 60 from one disk of one set to a disk of the other set, each disk of each set being mounted one upon another and each having an annular flange formed on its upper face.

5. In a drier, a chamber, means to heat the

chamber, sets of rotatable disks in the chamber, the disks of one set having a portion of their peripheral edges overlapping similar portions of the disks of the other set, means to feed articles to the uppermost disk of one set, and means to transfer the articles from the disks of one set to the disks of the other set alternately to transfer the articles over a zig-zag course from the uppermost disk of one set to the lowermost disk of the other set, each disk of each set being mounted one 65 upon another and each having an annular flange formed on its upper face.

6. In a drier, a chamber having an inlet and an outlet, means for heating the chamber, means for feeding articles to the chamber, sets of disks rotatably mounted on the chamber, each disk having an annular flange on its upper face, means for rotating the sets of disks in opposite directions, and a trip co-operating with each disk and whose inner 80 end lies close to the annular flange of the respective disk to transfer the articles from the disks of each set alternately.

7. In a can end drier, a chamber, means to heat the chamber, sets of rotatable disks in the chamber, means for rotating the disks in opposite directions, an upright mounted in the chamber, and trip arms secured to the upright and arranged whereby one trip will 90 co-operate with one disk and whereby can ends are transferred from one disk of one set to a disk of the other set.

8. In a can end drier, a table, a chamber mounted on the table, a closure for the chamber, a heating means arranged in the chamber, sets of rotatable disks in the chamber, the disks of one set having a portion of their peripheral edges overlapping similar portions of the disks of the other set, means to feed can ends to the uppermost disk of one set and means to transfer the can ends from one disk of one set to a disk of the other set alternately and thereby transfer the articles over a zig-zag course from one disk of one set to another disk of the other 100 set.

9. In a can end drier, a table, a chamber mounted on the table, a closure for the chamber, a heating means arranged in the chamber, sets of rotatable disks in the chamber, the disks of one set having a portion of their peripheral edges overlapping similar portions of the disks of the other set, means to feed can ends to the uppermost disk of one set, and trip arms to transfer the can ends from one disk of one set to a disk of the other set alternately and thereby transfer the articles over a zig-zag course from one disk of one set to another disk of the other 115 set.

10. In a drier, a chamber, sets of rotatable disks in the chamber, means for rotating the disks in opposite directions, means to trans-

fer articles from one disk of one set to a disk of the other set alternately to transfer articles over a zig-zag course from the uppermost disk of one set to the lowermost disk of the other set, and means whereby the articles may be dried during their zig-zag movement from one set of disks to the other.

Copies of this patent may be obtained for five cents each, by addressing the "Commissioner of Patents, Washington, D. C."

In testimony whereof I affix my signature in presence of two witnesses.
